City.

UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

SEPARABLE FASTENER.

1,387,116.

Specification of Letters Patent. Patented Aug. 9, 1921.

Application filed January 16, 1920. Serial No. 351,787.

To all whom it may concern:

Be it known that I, FRED S. CARR, a citizen of the United States, and resident of Newton, in the county of Middlesex and 5 Commonwealth of Massachusetts, have invented an Improvement in Separable Fasteners, of which the following description, in connection with the accompanying drawings, is a specification, like characters on the 10 drawings representing like parts.

This invention pertains to improvements in separable fasteners.

It is among the objects of the invention to provide an improved fastener of simple 15 and rugged construction in which the parts are locked against separation by lateral strain in at least one determined direction and preferably in more than one determined direction.

20 In the drawings, which show a preferred embodiment of one form of my invention:

Figure 1 is an elevation of two pieces of fabric held together by a preferred form of fastener;

25 Fig. 2 is a section on the line 2—2 of Fig. 1;

Fig. 3 is a section on the line 3—3 of Fig. 2, showing the socket and the neck of the stud in their normal position when not under 30 strain; and

Fig. 4 shows the parts of the socket when under lateral strain in a direction toward the left of said figure.

Referring to the drawings and to the preferred form of my invention selected for 35 illustrative purposes, I have shown the stud

5, which may be of any suitable form and secured to the stud-carrying fabric 6 in any suitable way, but preferably by an expandable base 7 wedging the fabric 6 within a stud-securing cap 8. The preferred form of 40 socket herein shown includes a casing 9 secured to stud-carrying fabric 10 in any suitable way, as by sewing, but preferably by 45 stud-securing prongs 11 flanged over to press

the stud-securing fabric over a lip on any suitable stud-securing cap 12. The stud-securing casing 9 preferably incloses a spring 13, which is preferably flat and provides a stud-receiving aperture 14 and which 50 is preferably split at one side at 15.

The preferred form of socket herein shown preferably provides for coöoperating cam surfaces between the spring and coöperating parts, such cam surfaces being

adapted to hold the spring 13 closed under lateral strain in at least one direction, and preferably in more than one direction.

In the preferred form of socket herein illustrated, the cam surfaces on the spring 60 13 may include cam surfaces 18 and 19, corresponding to similar cam surfaces on the spring shown in the application of Andrew G. Anderson, filed herewith, Serial No. 351,786. These cam surfaces may coöperate 65 with cam surfaces 16 and 17, which may conveniently be provided by a ring 20, which may be stamped from sheet metal and inclosed in the casing. I also preferably provide cam surfaces 21 and 22 on the spring 70 70 adapted to coöperate with coöoperating cam surfaces 23 and 24, which may conveniently also be provided by the stamped sheet metal ring 20. When lateral strain is exerted between the stud and socket in such a direction as to move the spring to the left in the socket casing, as shown in Fig. 4, the cam surfaces 16 and 17 abut against the cam surfaces 18 and 19, thereby tending to keep the spring closed. When strain is exerted 75 in a direction tending to move the spring to the right in the socket casing, as viewed in Fig. 4, the cam surfaces 21 and 22 abut against the coöoperating cam surfaces 23 and 24 and tend to close the spring and prevent 80 85 undesired separation of the stud from the socket.

It will be understood that I use the word "fabric" in its broader sense to include not only woven materials, but any flexible carrying medium.

While I have shown and described a preferred form of one embodiment of my invention, it will be understood that changes involving omission, substitution, alteration 95 and reversal of parts and even changes in the mode of operation, may be made without departing from the scope of my invention, which is best defined in the following claims.

Claims:

1. A separable fastener comprising, in combination, a stud having a head and a neck, and a socket containing a spring, said spring providing a stud-receiving aperture 105 and an opening at one side thereof, said spring having oppositely disposed cam surfaces on each side of the opening, said cam surfaces all located on projections from the spring and adapted to coöperate with corre- 110

sponding cam surfaces independent of the spring.

2. A separable fastener comprising, in combination, a stud having a head and a neck, and a socket including a casing and a spring carried thereby having a stud-receiving aperture and an opening at one side thereof to permit expansion and contraction of the stud-receiving aperture, a ring between the sides of the casing and the sides of the spring, said ring permitting expansion and contraction of the spring when not under lateral strain, but opposing expansion of the stud-receiving aperture when lateral strain is exerted between stud and socket in a direction toward the opening in the spring.

3. A separable fastener comprising, in combination, a stud having a head and a neck, and a socket including a casing and a spring carried thereby having a stud-receiving aperture and an opening at one side thereof to permit expansion and contraction of the stud-receiving aperture, a ring between the sides of the casing and the sides of the spring, said ring permitting expansion and contraction of the spring when not under lateral strain, but opposing expansion of the stud-receiving aperture when lateral strain is exerted between stud and socket in a direction away from the opening in the spring.

4. A separable fastener comprising, in

combination, a stud having a head and a neck, and a socket including a casing and a spring carried thereby having a stud-receiving aperture and an opening at one side thereof to permit expansion and contraction of the stud-receiving aperture, a ring between the sides of the casing and the sides of the spring, said ring permitting expansion and contraction of the spring when not under lateral strain, but opposing expansion of the stud-receiving aperture when lateral strain is exerted between stud and socket in a direction either toward or away from the opening in the spring.

5. A separable fastener comprising, in combination, a stud having a head and a neck, and a socket including a casing and a spring carried thereby having a stud-receiving aperture and an opening at one side thereof to permit expansion and contraction of the stud-receiving aperture, a ring rotatable in the casing and located between the sides of the casing and the sides of the spring, said ring permitting expansion and contraction of the spring when not under lateral strain, but opposing expansion of the stud-receiving aperture when lateral strain is exerted between stud and socket in a direction toward the opening in the spring.

In testimony whereof, I have signed my name to this specification.

FRED S. CARR.
